GLOBE STRUCTURE.

Application filed March 18, 1925. Serial No. 16,408.

Our invention relates to lighting fixtures and particularly to a housing for enclosing electric light units.

The principal object of our invention is to provide a closed globe for street-lighting units that is provided with means for protecting the globe by preventing moisture from running down it.

Another object of our invention is to provide a globe entirely of glass, which is closed in order that dust cannot collect inside of the globe and which is, however, accessible for the replacement of lamps.

Heretofore, lamp-post tops have been provided with substantially cylindrical globes of glass which were mounted on the lamp-post and were surmounted by metal canopies. Another type comprised metal frame members upon which the glass walls of the globe were mounted. The top or canopy of the latter fixture comprised frame members and panels which were either of transparent or non-transparent material. Another form of fixture for lamp posts was a spherical globe that was secured to the lamp-post and formed an entirely closed glass unit. In all of these forms of fixtures, the sides of the globe soon became streaked from dust and from moisture running down the globe. In some forms of globes, the walls became overheated and, when drops of moisture struck the globes, breakage resulted by reason of the sudden cooling.

Our invention constitutes an improvement in lamp-post globes and comprises a globe or top entirely of glass, which is provided with means for protecting the globe from moisture and dust. The globe, therefore, is not streaked by the moisture which runs down from the canopy, nor is it broken by reason of drops of moisture striking the heated globe wall. The housing is made in two parts, and provides means for permitting convenient disassembling and also replacement of lamps.

In the drawing constituting a part hereof, and in which like numerals designate like parts,

Figure 1 is an elevational view of our lighting fixture, a portion thereof being shown in section,

Fig. 2 is a plan view of a ring-shaped holder that secures the globe and canopy together, and

Fig. 3 is an enlarged cross-sectional view of the globe flange and the holder, showing in

detail the manner of connecting the globe and canopy together.

Our lighting fixture comprises a glass globe 1 and a canopy 5 that are held together by a ring-shaped holder or band 7 and are secured to the lamp-post top 2 by means of screws 3. The globe may be made of either plain, stippled or opal glass, and has an outwardly flaring bell-shaped wall that terminates at the top in a flange 4. The top portion or 60 canopy 5 is of glass similar to the globe 1, is conically shaped and has an outwardly extending flange 6 of greater diameter than flange 4 and so shaped that an overhanging ledge is formed.

The globe and canopy are held together by a holder (which is described in detail and claimed in application Serial No. 683,902 by John R. Townsend, filed January 2, 1924, and assigned to the George Cutter Company of 70 South Bend, Indiana). The holder comprises a band 7 having short channel-shaped sections 9 suitably spaced apart and attached thereto by rivets 10. The sections 9 form U-shaped fingers that fit around the glass 80 flanges 4 and 6 to hold the globe and canopy together, as best shown in Fig. 3. One end of band 7 is provided with an opening 13 into which a curved or up-struck tongue 14 is hooked for holding the globe and canopy together.

In assembling the fixture, the globe 1 is attached to the lamp post by means of screws 3. Canopy 5 is placed on globe 1 and the band 7 is wrapped around the flanges 4 and 6, and 90 fastened to hold the globe and canopy together. In order to remove the holder the ends of band 7 are pressed inwardly so that the hook 14 is disengaged. The band then loosens and allows fingers 9 to disengage 95 flanges 4 and 6.

Our lamp-housing comprises a two-part structure entirely of glass. The globe is of inverted bell-shape, so that rain or moisture falling or running down from the canopy is 100 prevented from striking the globe. A conically shaped canopy of glass is provided with a flange that fits over the upper globe flange and forms an over-hanging drip-ledge, which prevents moisture and drippage from 105 running down the globe wall.

Although we have described a specific embodiment of our invention, we do not wish to be limited thereto, as modifications of the specific form of canopy, globe-holder or ledge 110

may be made. Other modifications of our invention will suggest themselves to those skilled in the art without departing from the spirit of the invention, the scope of which is defined in the annexed claim.

5 We claim as our invention:

A lamp housing comprising a globe having an outwardly and upwardly extending flange, a top for said globe having a ledge adapted 10 to rest upon and to extend over said flange to protect the exterior of said globe from mois-

ture, and a removable metal band for uniting said globe and said top provided with clips for engaging the globe and top, said clips having downwardly, outwardly extending portions for leading moisture away from the junction of top and globe.

In testimony whereof, we have hereunto subscribed our names this 19th day of February, 1925.

FRANCIS R. HEALEY.
WALTER E. BEATY.
